UNITED STATES PATENT OFFICE.

MORRIS M. GRUBER, OF BROOKLYN, NEW YORK, ASSIGNOR TO THE BURWOOD CORPORATION, OF SCRANTON, PENNSYLVANIA, A CORPORATION OF NEW YORK.

MOTION-PICTURE-PROJECTING MACHINE.

Application filed April 5, 1919, Serial No. 287,850. Renewed December 23, 1925.

This invention relates to improvements in motion picture apparatus generally, and in particular to a greatly simplified projecting machine.

5 The numerous and varied types of movements that are necessary to properly feed a picture film strip through a projecting machine and provide the necessary intermittent movement of the film, have heretofore been 10 produced in actual practice by complicated mechanism including a great many gears and corresponding main and counter shafts. The uncompensated multiplication of gears and shafts produces a very objectionable vibration and unsteadiness of the projecting apparatus that is greatly magnified and exaggerated in its effects in the pictures appearing on the screen. In order to overcome as far as possible the vibration referred to, it has been the practice to form 15 the supporting parts for the operating parts of the projecting machines on a comparatively massive and heavy scale, with the result that the apparatus in general use has 20 not only been complicated because of the large number of gear wheels made use of, which also rendered it impossible to quickly take the machine apart for emergency repairs or for any other purpose while operating, but the machines have necessarily been 25 exceedingly heavy and cumbersome. In addition, the excessive number of gears and other operating parts has tended to produce rapid wear in the machine, so that in a short 30 time loose play was established which also tended to produce vibration.

In the course of experiments conducted for the purposes of this invention, I have discovered that the number of operating 40 parts in the form of gears and shafts can be very materially reduced over the number heretofore used, so that the unsteadiness, and consequently the need of adding to the size and weight of the operating parts, is correspondingly decreased. I attain this by making use of a main drive shaft of a substantial and rigid construction and which has a length substantially equivalent to the length of the framework of the machine and is 45 journaled at a plurality of points in bearing members integral with the framework and providing bearing surfaces of substantial 50 length. The main drive shaft referred to is mounted in a vertical position, that is, in a

substantially parallel position with relation to the longest axis of the machine so that, not only is an opportunity had to provide for an adequate bearing support which will effectively prevent vibration of the shaft, but this arrangement is further utilized in 55 driving every operating part directly from the main shaft without the use of intermediate gears.

I not only achieve this but I have discovered that I can secure an exceedingly 60 effective and thorough application of the principle of the worm-drive to the apparatus and thereby secure a still greater degree of 65 steadiness and smoothness of operation of the mechanism. For this purpose the main 70 drive shaft is supplied with worm-cut teeth, either formed directly in the body of the shaft or in gears mounted to turn directly with the shaft, and which directly engage 75 corresponding spiral gears carried by the shafts of the film and shutter operating mechanisms. I even apply the worm-drive principle to the operation of the drive shaft and effect this by reversing the usual construction in that a manually operable drive 80 shaft is supplied with a spiral toothed gear wheel which engages at any desired velocity ratio, a worm cut directly in the main drive shaft, so that the spiral gear is the driving 85 and the worm the driven member, instead of the worm serving as a driving member as in ordinary practice.

In addition to the simplified operating mechanism by which a single drive shaft directly operates every moving part in the 90 machine by means of smoothly-engaging worm and spiral gears and thereby produces an extremely high degree of steadiness in operation, I also provide for an easy accessibility to, or a ready and rapid removal of a 95 combined intermittent motion and framing device which forms an important feature of the invention, for any emergency adjustments or repairs that may be required under operating conditions. For this purpose the 100 intermittent motion device which forms one of the most important operating parts in the apparatus, is preferably self-contained in a unitary frame or casing that is adapted to be fitted into and firmly held against vibration in a seat formed for the purpose in the main framework of the machine. This arrangement provides for the ready removal

of the intermittent motion device as a unit from its position, by the release of a simple holding member and, in addition, the relation of the seat to the main driving shaft is such that the intermittent motion device can be moved or turned in its seat for framing purposes without interfering with the driving connection between the shaft and intermittent motion device.

- 10 Other features of the invention comprise a novel and effective mounting for the aperture plate of the film gate and the provision of easily detachable pressure springs for the film tension plate.

15 In the drawing,

Figure 1 is a front elevation, partly in section, of a motion picture projecting machine embodying my invention.

Figure 2 is a side elevation taken from

- 20 the left hand side of Figure 1.

Figure 3 is a vertical section of a portion of the machine showing the manner of mounting the intermittent motion device.

- Figure 4 is a longitudinal

Figure 5 is a view in elevation of a detail showing the manner of seating the film aperture plate.

30 aperture plate.

In the drawings I have shown a motion-picture-projecting machine in which a main drive-shaft 1 is mounted in a vertical position in the thrust-bearing 2 formed on the base 3 of the machine and is additionally journaled in the brackets 4 and 5 formed integral with the web or partition 6 which connects the base member 3 and the upper plate 7 of the framework of the machine.

- The drive-shaft 1 is provided either with worm teeth formed directly in the surface thereof, or with spiral gears through which the four operating elements of the machine are directly driven and by which the shaft is itself directly driven preferably from the manually-actuated operating shaft 8. I also distribute the various driving connections in a symmetrical or balanced arrangement along the length of the shaft, the upper film-feeding sprocket 9 together with the shutter-operating shaft 10 being operated from worm 11 and spiral 12 driving elements located near the upper end of the shaft, and the lower film sprocket 13 together with the intermittent motion device 14 being driven from the lower end of the shaft, while the shaft is driven through a spiral wheel and worm unit located substantially at the middle portion of the shaft and intermediate the two sets of driving elements referred to.

50 By means of the construction described—that is, with the drive-shaft so arranged as to form through worm drive connections the direct and only power shaft between the manually-operated shaft 8 and the various operating elements—I am enabled not only

to produce a device for this purpose having a greatly simplified construction and with the number of driving parts reduced to a minimum, but I also succeed in producing an extremely smooth-running and steady group of operating parts. The steadiness of operation referred to is due partly to the extremely low number of operating parts which I have succeeded in employing to accomplish all that has heretofore been accomplished with a much greater number of operating elements. Another factor contributing to the steadiness of operation characteristic of my machine resides in the use in every instance where a driving connection is employed of worm and spiral gears with their attendant smoothness and freedom from loose play.

I have succeeded in still further insuring steadiness and compactness of operation by taking advantage of the absence of the usual number of parts by utilizing the space thus provided for supporting the horizontal driving and driven countershafts in bearing members of extended length and which for the most part are formed integral with the substantial web frame member 6 already referred to. Thus, the bearing members 15, 16 and 17 support, respectively, the shafts for the upper feed sprocket 9, the manually-operated drive-shaft 8, and the lower film feed sprocket 13. The very considerable length of the bearing member provides an extremely rigid support for the various shafts and contributes in no small degree to the steadiness of operation of the mechanism, as will be clear.

As has already been noted, I preferably drive the main shaft 1 through the manually-operable shaft 8, to which is attached a spiral toothed wheel 18 meshing with a worm 19 formed directly on the shaft 1, substantially midway of its length. The reversal of the usual construction—that is, the employing of the spiral wheel as the driving member and the worm as the driven member—I have found to be very effective in this situation, and with a suitable velocity ratio, such as four to one, I can secure a powerful drive with the expenditure of a comparatively small amount of energy. A handle, such as is shown at 20, and which can be readily connected and disconnected through the bayonet joint shown at 21, is preferably used to turn the shaft 8.

The upper feed sprocket 9 is driven from a worm 11 formed directly on the main drive-shaft 1, as has already been noted, and the worm 11 meshes with a spiral gear 22 for this purpose. Likewise, the lower feed sprocket 13 is driven from a worm 23 formed near the lower extremity of the shaft 1 and which meshes with a spiral gear 24 mounted on the shaft which carries the sprocket 13. A pulley 25 is preferably also 130

carried by the spiral gear 24 from which a belt may be led to the lower film reel mounted beneath the projector. In addition, a spiral gear 12 fixed to the drive-shaft 1 at 26 meshes with a corresponding gear 27 carried by the shutter-operating shaft 10. Not only do the worms 11 and 23, adjacent the opposite ends of the shaft 1, balance each other but the spiral gear 12 also has its 10 counterpart in the spiral gear 28 mounted on the shaft 1 at about the same distance below the driving spiral gear 18 that the gear 12 is mounted above the spiral 18. The spiral gear 28 is arranged to directly mesh 15 with and drive a worm 29 formed on the main shaft 30 of the intermittent motion device 31 of which the sprocket 14 forms a part.

One of the most important features of 20 my invention resides in the extremely simple and compact operating mechanism which has been above described. Another important feature of the invention resides in the combined intermittent motion and framing device 31, whose double function it is to directly produce in the film strip the alternate quick movement and dwell that is characteristic of the operation of motion-picture-projecting machines, and to register the picture section with the window aperture in 25 the film gate. The combined intermittent motion and framing device 31 has been embodied in a simple, self-contained structure that can be removed from and replaced in its 30 position in the group of mechanism as a single unit and without disturbance in any way of any other operating part. To achieve this, I mounted the intermittent driving mechanism for the film-operating sprocket 14 in a unitary casing 32 having a very solid 35 and substantial construction and presenting a bearing support of comparatively great length for the main shaft 30 in the device. Not only is a substantial framework and 40 solid support thus secured for the important intermittent sprocket-operating mechanism, but an equally substantial and adequate support for the casing 32 of the intermittent motion device is also provided. This support is furnished directly by the main frame 45 web member 6 and takes the form of a seating opening 33 of comparatively large diameter. In order to cooperate with the seating opening 33 in the web member 6, the 50 frame or casing 32 of the intermittent motion device is made correspondingly large and is provided with a groove 34 formed by flanges 35 in which is received the edge of 55 the web member forming the seat opening 33. It will be seen that the comparatively 60 large seat which is thus provided for the reception of the intermittent motion device will be very effective in preventing vibration or other movement of the device with 65 relation to the frame member in which it is

mounted, thus providing a very stable and rigid mounting for the device.

Not only does the seating arrangement referred to secure a very solid and immovable mounting for the intermittent motion device, 70 but it also provides a very effective framing structure. To produce a framing operation by which the picture sections of the film are placed in register with the aperture 36 in the film plate 37, it is necessary merely to 75 rotate the intermittent motion device as a whole in its seat 33 by which the intermittent motion sprocket, which is eccentrically mounted in the casing 32, is moved upwardly or downwardly to correspondingly move the 80 film 46 and produce the framing effect. To provide for this, the casing 32 is frictionally held against accidental rotation in its seat 85 but not so firmly as to prevent its rotation through the link 38, crank 39, shaft 40, and handle 41, at the will of the operator. The casing 32 is cut away, as at 45 and 47, to provide for operating engagement of the worm 29 on the shaft 30 and the spiral gear 28 on the main drive-shaft 1, as well as to 90 permit the rocking of the frame 32 in its seat without striking the shaft 1. Preferably, a cut-out portion 48 on one of the seating flanges 35 cooperates with a pin 49 on the web 6 to prevent excessive movement in 95 a framing operation, the limit of movement being substantially the length of a picture section. While I have described the framing operation as being produced by a rotation of the intermittent motion device in its seat, I do not limit myself to this specific construction, but may provide for framing by a bodily movement of the device in its seat—that is, by a movement by translation 100 in lieu of or combined with a rotating movement.

The casing 32 is held in its seat by the follower 41' which has an arc-shaped formation corresponding to the adjacent face of the groove 34 and which is also provided 110 with a spring 42' for normally holding the casing against rotation. Suitable screws 43' pass through flanges 44 on the follower 41' into the web member 6 and are locked against movement by the action of the spring 42'.

It will be seen that the follower 41' can be removed by the simple expedient of removing the two screws 43' and the intermittent motion and framing device 31 quickly removed from its seat and from its operating engagement with the main drive-shaft 1. This simple means for disassembling this 120 important operating mechanism without disturbing other operating elements is a very important feature of the invention.

The internal construction of the intermittent motion device is very simple and consists of the main concentrically-journalized shaft 30 carrying the cam and pin wheel 47' of a Geneva stop-device which includes the 125

star-wheel 48' carried on the sprocket shaft 49'. The Geneva stop device is contained in a chamber 50 in the casing 32 which is adapted to be filled with oil and in which is included a thrust-bearing 51 for the shaft 30. The specific form of intermittent motion I find particularly well adapted for this purpose because it does not jerk the film but has a gradual acceleration and retardation of motion.

The main shaft 30 of the intermittent motion and framing device preferably carries at one end a fly-wheel 55 in which is contained speed-controlled mechanism for operating a 15 fire shutter 56 through an arm 57 and any suitable connection, this mechanism forming of itself no part of my invention herein disclosed.

I also provide a very solidly mounted 20 aperture-plate 52 for the film gate 37 which has a dove-tailed connection with the gate and can be pushed into place from one side and held in normal position by means of the latch 54.

25 Another feature of the invention resides in the use of easily removable spring-members 58 carried by the film-pressure plate 59. This detachability of the spring members 58 adds to the easy assembling of my device 30 and provides for the ready replacement of the spring in case of breakage or for any other reason. It will be noted that the door member 60 which carries the film-pressure plate 59 is hinged at the bottom of the machine framework in order to provide accessibility to the intermittent motion device. A 35 suitable catch 61 is provided for latching the door in its closed position.

I preferably provide an opening, as at 62, 40 in the top of the machine framework through which, when the cover-plate 63 is removed, the main drive-shaft 1 can be lifted for any purpose. The upper film reel is preferably attached to the top of the framework by means of the clamping-screw 64 passing through the flange 65 on the base of the reel. As the film passes down into the projecting machine, it is held against the top feed-sprocket 9 by the pressure arm 66 carrying the roller 67. A cam member 68 carried by the pressure arm cooperates with a suitable spring 69 for holding the arm in either a film-engaging or disengaging position. Similar pressure arms 70 and 71 50 operate, respectively, with the intermittent motion sprocket 14 and the lower film-feeding sprocket 13 for a like purpose. Corresponding cams 72, 73, and springs 74, 75, are also made use of, while a handle member 76 55 is provided in connection with the pressure arm 70.

Having thus described my invention, what is claimed is:

1. In a motion picture machine, a framework including a base member and a vertical supporting member, a vertically mounted main drive shaft having the lower end thereof journaled in said base member, a laterally extending bracket carried by said vertical supporting member in which the upper end of said shaft is journaled, worm teeth cut directly in said shaft at the upper end thereof, film feeding means having a direct gear connection with said worm teeth, worm teeth cut directly in said shaft near the middle portion thereof, shaft driving means geared directly with said worm teeth, worm teeth cut directly in said shaft near the lower end thereof, and film feeding means having a direct gear connection with 75 said worm teeth, said driving means engaging the side of the shaft opposite that engaged by the film feeding means, whereby vibrations in the shaft are overcome.

3. In a motion picture machine, a framework including a base member and a vertical web member, a vertically mounted main drive shaft having the lower end thereof journaled in said base member, a pair of spaced-apart laterally extended bracket 90 members mounted on said vertical web member, the upper end of said shaft being journaled in said bracket members, film feeding devices having worm gear connections with the upper and lower end of said shaft, shaft driving means having worm gear connections with a middle portion of said shaft, and shutter driving means having worm gear connections with said shaft between said spaced-apart bracket members.

3. In a motion picture machine, a framework including a base member and a vertical web member, a vertically mounted main drive shaft having the lower end thereof journaled in said base member, a thrust bearing in said base member for the lower end of said shaft, a pair of spaced-apart laterally extended bracket members mounted on said vertical web member, said shaft being journaled in said bracket members near its upper end, film feeding devices having worm gear connections with the upper and the lower ends of said shaft, shaft driving means having worm gear connections with a central portion of said shaft, an intermittent sprocket device having a worm gear connection with a central portion of said shaft opposite said shaft driving connection, and shutter driving means having worm gear connections with said shaft between 110 said spaced-apart bracket members.

MORRIS M. GRUBER.
